THERAPEUTIC MACHINE HAVING BED-OVER-HANGING BODY-CONTACTING HEAD FOR STIMULATING BLOOD CIRCULATION

Louis E. Holland, Lee's Summit, Mo.

Application March 8, 1954, Serial No. 414,568

3 Claims. (Cl. 128—55)

The present invention has to do with therapeutic apparatus and more particularly to structure for stimulating blood circulation and relieving tension and soreness in muscles similarly to the disclosures of my Patent No. 2,657,685, issued November 3, 1953, and my copending application Serial No. 352,788, now Letters Patent No. 2,671,443.

This is a continuation-in-part of my said co-pending application and has for its primary object the carrying forward of the principles therein disclosed into a machine that has still wider uses in the field of therapeutics by its particular adaptability for treatment of bed patients or other disabled persons who are unable to conveniently employ the machines of my said prior disclosures.

It is an important object of the present invention to provide a massaging machine having a novel support or mount rendering the rotatable massager itself maneuverable to the extent that the same may be positioned wherever desired with respect to the body of the person to be treated thereby.

Another important object of the present invention is the provision of a therapeutic machine having a rotatable massager mounted on a carriage that is not only swingable on its support, but reciprocable therealong and rotatable on the support for the purpose of permitting virtually any desired positioning of the massager.

A further object of the instant invention is to provide a massaging machine wherein the carriage upon which the massager is rotatably mounted is balanced on its support in two directions, not only by selecting a center of gravity for swinging movement, but by provision of a counterweight that helps hold the carriage in selected positions along its reciprocable path of travel on the support.

Other objects include many important details of construction, all of which will be made clear or become apparent as the following specification progresses, reference being had to the accompanying drawing, wherein:

Figure 1 is a side elevational view of a therapeutic machine having bed-overhanging body-contacting head for stimulating blood circulation made pursuant to the present invention.

Fig. 2 is a top plan view thereof.

Fig. 3 is an end elevational view thereof.

Fig. 4 is an enlarged, fragmentary, horizontal, cross-sectional view through the carriage.

Fig. 5 is a fragmentary, vertical, cross-sectional view through the carriage and its support at the point of intersection and still further enlarged.

Fig. 6 is a vertical, cross-sectional view through the support or standard at its uppermost end.

Fig. 7 is an enlarged, fragmentary, elevational view of the standard and the carriage mount looking in the direction of the motor housing; and

Fig. 8 is a fragmentary, cross-sectional view taken on line VIII—VIII of Fig. 7.

The general purposes of the present invention, so far as therapeutic value of the instant invention is concerned,

are the same as set forth in my prior disclosures above-mentioned and said disclosures are, therefore, incorporated herein by way of reference. In this respect, therefore, a rotatable massager broadly designated by the numeral 10, may take the general form of either of said prior disclosures and need not further be described in detail. It is sufficient to point out that the massager 10 includes a rotatable shaft 12 provided with a plurality of flexible paddles 14 that extend radially from the shaft 12 when the latter is rotating.

In accordance with the principles of the present invention the rotatable massager 10 is mounted on a carriage broadly designated by the numeral 16 that is in turn attached to a support 18 for movement relative thereto in a plurality of directions. The support 18 includes a base 20 that may be provided with a plurality of caster wheels 22 for rendering the support 18 mobile. Base 20 carries an elongated, preferably tubular standard 24, and it is upon the standard 24 that carriage 16 is swingably, rotatably and reciprocably mounted.

Carriage 16 includes a housing 26 for a prime mover such as a reversible electric motor 28, together with a pair of spaced, laterally extending arms 30 and 32 that are likewise preferably tubular. The means for operably coupling the prime mover 28 with the massager 10 shown in Fig. 4 of the drawings, includes a shaft 34 rotatably mounted within the arm 30 and having a pulley 36 within the housing 26 that receives an endless belt 38 also trained around a pulley 40 on the drive shaft of motor 28. The shaft 12 of the massager 10 which is rotatably carried by the arms 30 and 32 is provided with a worm gear 42 that meshes with a worm 44 on the shaft 34.

The means for operably mounting the carriage 16 upon the standard 24 includes first an element in the nature of a collar 46 slidable on the standard 24 for reciprocation longitudinally thereof. A pair of cables 48 attached at one end thereof to the collar 46, extends upwardly along the standard 24 exteriorly thereof around pulleys 50 carried by the standard 24 and thence downwardly into the standard 24 for connection with weight means 52 freely reciprocable within the standard 24.

The collar 46 embraces and mounts a sectional member in the nature of a sleeve 54 that is in turn provided with a pair of diametrically opposed, internally tapped bosses 56 and 57. The bosses 56 and 57 swingably receive a pair of opposed plates 58 and 60 through the medium of pintles 62 attached to the bosses 56 and 57. Plates 58 and 60 are rigidly secured to the housing 26 as is seen in Figs. 1 and 2 of the drawings.

That end of the plate 60 remote from the housing 26 is provided with a semi-circular extension 64 that cooperates with extensible structure broadly designated by the numeral 66 for releasably holding the carriage 16 rigidly attached to the standard 24. Boss 56 carries a swingable yoke 68 that depends therefrom and which in turn receives a hollow block 70 at its lowermost end interposed between plate extension 64 and the standard 24 as best seen in Fig. 5.

60 A rod member 72 traverses the block and is provided with a fingerpiece 74. Rod 72 rotatably carried by the block 70 is rectangular in cross-section as shown in Fig. 5 within the block 70 and the latter carries a pair of spacers 76, one on each side of the rod 72. A pair of resilient discs 78 made from leather or other suitable material, are interposed between the spacers 76 and the rod 72. Similarly, a disc 80 engages the plate extension 64 and a disc 82 similar to discs 78 and 80, is interposed between the standard 24 and the proximal spacer 76.

70 An arch member 84 carried by the arms 30 and 32 mounts a heat lamp 86, such as infrared above the rotatable massager 10 and having a guard 87. The lamp

86 may be controlled by an electric switch 88 and the reversible motor 28 may be controlled by a switch assembly 90 both carried by the arm 32.

The means for operably coupling the motor 28 and the lamp 86 with a source of electrical energy is not herein illustrated, but it may be pointed out that any suitable slip ring or equivalent commutator connection of conventional character may be employed to permit the various movements of carriage 16 without danger of entanglement of any of the necessary conductor wires used in such coupling assembly.

While it is preferred that the pintles 62 be located substantially at the center of gravity of carriage 16 between housing 26 and massager 10, and while it is also desirable that the counterweight 52 be substantially as heavy as the carriage 16 and its component parts, carriage 16 may be held against all movement with respect to the support 18 simply by rotation of the rod 72 through use of the fingerpiece 74 to the position illustrated in Fig. 5 of the drawings. When the rod 72 is in such position the spacers 76 and the discs 78, 80 and 82 are expanded outwardly spanning the distance between the extension 64 and the standard 24 and wedged tightly in place to prevent rotation of the plate 64 with respect to the standard 24.

The extensible locking structure 66 that binds between the extension 64 and the standard 24, also holds the carriage 16 against rotation and reciprocation with respect to the standard 24. Ninety degree rotation of the control rod 72 releases the locking means 66 whereupon the carriage 16 may be freely swung on the aligned axes of pintles 62 that intersect the standard 24 radially thereof. Such release of the locking means 66 also permits free rotation of the carriage 16 around the collar 46 and around the longitudinal axis of the standard 24 by virtue of the free rotational fit of the sleeve 54 on collar 46.

Still further, when the lock 66 is released, the carriage 16 may be moved bodily along the longitudinal axis of standard 24 because of the sliding arrangement between the collar 46 and the standard 24. It is important to note at this point that swinging movement of the standard 16 on pintles 62 and rotational movement of the carriage 16 around the collar 46, does not adversely affect the cables 48 since the collar 46 remains stationary on the standard 24 during swinging and rotational movement of the carriage 16.

It can now be appreciated that the massager 10 may be disposed in virtually any desired selected position so that all parts of the body of the user may be reached and upon energization of motor 28, the flexible paddles 14 brought into gentle slapping and patting engagement with all parts of the body.

It can now be appreciated that the therapeutic machine above described is particularly adapted for use by persons in a prone or supine position since the carriage 16 which extends laterally outwardly from the standard 24 may be positioned in overlying relationship to a bed sim-

ply by moving the entire machine into position through use of the roller means 22.

Still further, while the massaging machine forming the subject matter of the present invention has been designed especially for use in connection with beds and the like, the maneuverability of carriage 16 permits the employment of the massager 10 while the user is either standing or sitting, particularly since the carriage 16 may be swung on the pintles 62 through a wide arc concentric with the axes of the pintles 62. The balance that is provided by use of the counterweight 52 and by proper positioning of the pintles 62 with respect to the center of gravity of carriage 16, facilitates use of the machine and permits adjustments of the carriage 16 relative to the support 18 with ease and without consumption of undue energy or time.

Still further, as set forth in my copending application Serial No. 352,788, the disposition of the massager 10 within the rays of heat emanating from lamp 86 reduces the possibility of burn because of the way in which the paddles 14 interrupt the heat rays continuously while the massager 10 is rotating.

Having thus described the invention what is claimed as new and desired to be secured by Letters Patent is:

- 25 1. In a therapeutic machine, a vertical support; a collar surrounding the support and reciprocable vertically thereon; a carriage; structure mounting the carriage on said collar for rotation about the vertical axis of said support; a massager mounted on the carriage; pulley means on the support; cable means trained around the pulley means and secured to said collar; and weight means attached to the cable means for supporting the carriage.
- 30 2. In a therapeutic machine, a support; an element reciprocable on the support; a member rotatable on said element; a carriage; means pivotally mounting the carriage for swinging movement on said member; a massager mounted on the carriage; pulley means on the support; cable means trained around the pulley means and secured to said element; weight means attached to the cable means for supporting the carriage; and expansible means interposed between the support and the carriage for holding the latter rigid to the support.
- 35 3. In a therapeutic machine as set forth in claim 1 wherein is provided means mounting the carriage on said structure for swinging movement on a horizontal axis traversing the carriage and the support.
